US0D1069708S

(12) **United States Design Patent** (10) **Patent No.:** **US D1,069,708 S**
(45) **Date of Patent:** **** Apr. 8, 2025**

(54) **INVERTER GENERATOR**

(71) Applicant: **Chongqing Guoyu Technology Co., Ltd.**, Chongqing District (CN)

(72) Inventor: **Guolan Tang**, Chongqing (CN)

(73) Assignee: **Chongqing Guoyu Technology Co., Ltd.**, Chongqing (CN)

(**) Term: **15 Years**

(21) Appl. No.: **29/861,560**

(22) Filed: **Nov. 30, 2022**

(30) **Foreign Application Priority Data**

Oct. 18, 2022 (CN) 202230686969.4

(51) **LOC (15) Cl.** **13-01**

(52) **U.S. Cl.**

USPC **D13/112; D13/110**

(58) **Field of Classification Search**

USPC D13/112, 110, 114, 116, 108, 123, 162, D13/168, 169, 174, 177, 184, 199; D14/257, 432, 438

CPC H05K 5/00; H05K 5/02; H05K 5/0247; H05K 7/00; H05K 7/20; H05K 7/20136; H05K 7/20154; H05K 7/209; H05K 7/0042; H02M 7/00; H02M 7/003; H02M 2001/009; H02J 7/0042; Y10T 307/367; F02B 63/047; F02B 2063/045; F01N 1/026; F04G 17/05

(57) **CLAIM**

The ornamental design for an inverter generator, as shown and described.

DESCRIPTION

FIG. 1 is a perspective view of our new design, showing an inverter generator;

FIG. 2 is another perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view of the inverter generator, showing our new design.

Broken lines appearing in the various figures illustrate environmental or other features that form no part of the claimed design.

1 Claim, 8 Drawing Sheets
